[57] CLAIM

The ornamental design for a goaler skate, as shown and described.

DESCRIPTION

FIG. 1 is a perspective view of a goaler skate showing my new design;

FIG. 2 is a side elevational view thereof;

FIG. 3 is a side elevational view of the side opposite that shown in FIG. 2;

FIG. 4 is a bottom plan view thereof;

FIG. 5 is a top plan view thereof;

FIG. 6 is a rear elevational view thereof; and,

FIG. 7 is a front perspective view thereof shown on a slightly enlarged scale.
